[57] ABSTRACT

A die construction includes a body having first and second, opposite end caps and an extension member therebetween. The extension member has a first number of discrete facets and no more than the first number. Each of the discrete facets is identically shaped and have equal surface areas. The first end cap has a second number of discrete facets and no more than the second number. The second number is one-half of the first number. Each of the first end cap discrete facets is identically shaped and has an equal surface area to one another. The second end cap has the second number of discrete facets, that is, the same number as the first end cap, and has no more than the second number. Each of the second end cap discrete facets is identically shaped as the first end cap discrete facets. Each of the second end cap discrete facets has a surface area equal to a surface area of each of the first end cap discrete facets.

RANDOM NUMBER GENERATOR FOR GAME PLAYING

FIELD OF THE INVENTION

The present invention relates to devices for game playing. More particularly, the present invention relates to a random number generator for game playing. Specifically, the present invention relates to a die construction.

BACKGROUND OF THE INVENTION

There are numerous devices of different types that are useful for selecting at random a number, letter, or other character. Many of these are in the form of a die.

The traditional playing die is a cube-shaped, six-sided member. Through the years, dice of more than six sides have been developed, as the demand in various games of chance have necessitated. In U.S. Pat. No. 1,271,551 to Ebner, et al., a game die is disclosed in the form of an octagonal, rolling cylinder. U.S. Pat. No. 5,150,900 to Onzo discloses a heptahedron-shaped rolling cylinder for generating a random number.

Improvements are desirable.

SUMMARY OF THE INVENTION

The present invention is directed to a die construction that substantially obviates one or more of the problems due to the limitations and disadvantages of the prior art.

To achieve the advantages of the invention, and in accordance with the purposes of the invention, as embodied and broadly described herein, the invention comprises a die construction. The die construction includes a body having first and second, opposite end caps and an extension member therebetween. The extension member has a first number of discrete facets and no more than the first number. Each of the discrete facets is identically shaped and have equal surface areas. The first end cap has a second number of discrete facets and no more than the second number. The second number is one-half of the first number. Each of the first end cap discrete facets is identically shaped and has an equal surface area to one another. The second end cap has the second number of discrete facets, that is, the same number as the first end cap, and has no more than the second number. Each of the second end cap discrete facets is identically shaped as the first end cap discrete facets. Each of the second end cap discrete facets has a surface area equal to a surface area of each of the first end cap discrete facets.

Preferably, each of the extension member discrete facets includes printed indicia thereon. For example, this may take the form of a numbers or other markings, such as polka dots. The printed indicia indicate what number has been randomly generated.

In preferred arrangements, each of the extension member discrete facets is tapered. More preferably, each of the extension member discrete facets is triangular-shaped.

In certain preferred embodiments, each of the first and second end cap discrete facets is tapered. More preferably, each of the first and second end cap discrete facets is triangular-shaped.

In one preferred embodiment, the number of facets of the extension member is six. In such arrangements, the second number, that is, the number of discrete facets on the first end cap, is three. Three is also the number of discrete facets on the second end cap.

In other preferred arrangements, the number of facets of the extension member is 10, while the number of facets of each of the end caps is five.

In still other arrangements, the number of discrete facets of the extension member is 20, while the number of discrete facets for each of the end caps is 10.

Preferably, a ratio of a surface area of each of the extension member facets to a surface area of each of the first end cap discrete facets is about 2-3:1.

In preferred arrangements, the number of facets of the first end cap is equal to one-fourth of the total number of facets on the entire die construction. That is, the number of facets of the first end cap may be determined by totaling the number of facets of the first end cap, plus the number of facets of the second end cap, plus the number of facets of the extension member and then dividing that total by four. In such arrangements, the first and second end caps have an equal number of facets.

It is to be understood that both the foregoing general description and the following detailed description are exemplary and explanatory only and are not restrictive of the invention, as claimed. The accompanying drawings, which are incorporated in and constitute a part of this specification, illustrate example embodiments of the invention and together with the description, serve to explain the principles of the invention.

BRIEF DESCRIPTION OF THE DRAWINGS

FIG. 1 is a top plan view of a first embodiment of a die, embodying the present invention;

FIG. 2 is an end view of the die of FIG. 1, embodying the present invention;

FIG. 3 is an end view opposite of the FIG. 2 end view, embodying the present invention;

FIG. 4 is a perspective view of the FIG. 1 embodiment, embodying the present invention;

FIG. 5 is a side elevational view of the die of FIG. 1, embodying the present invention;

FIG. 6 is a perspective view of a second embodiment of a die construction, embodying the present invention;

FIG. 7 is an end view of the die of FIG. 6, embodying the present invention;

FIG. 8 is a side elevational view of the die of FIG. 6, embodying the present invention;

FIG. 9 is a side elevational view of the die construction of FIG. 6, embodying the present invention;

FIG. 10 is a perspective view of a third embodiment of a die construction, embodying the present invention;

FIG. 11 is an end view of the die construction depicted in FIG. 10, embodying the present invention;

FIG. 12 is a side elevational view of the die construction depicted in FIG. 10, embodying the present invention; and

FIG. 13 is a side elevational view, similar to that depicted in FIG. 12, but rotated, embodying the present invention.

DETAILED DESCRIPTION OF THE PREFERRED EMBODIMENTS

Reference will now be made in detail to the present preferred embodiments of the invention, examples of which are illustrated in the accompanying drawings.

In accordance with the invention, the invention is directed to a die construction. As embodied herein, a first embodiment of a die construction is shown generally in FIGS. 1-5 at 20. Die 20 includes a body construction 22 with a pair of opposite end members or end caps 24, 26. In extension between first and second end caps 24, 26 is a display member or extension member 28.

Extension member 28 functions to display indicia such as polka dots, or numbers or digits 30. The indicia 30 displayed is indicative of the number generated after rolling die construction 20.

The extension member 28 includes a plurality of discrete facets 32. Preferably, each of the discrete facets 32 are identically shaped and have equal surface areas to each other. That is, each of facets 32 has a surface area which is equal to and no greater and no less than the surface area of any other of the facets 32. Each of facets 32 is angled relative to an adjacent facet 32 to define corner or edge surfaces 34. Each of facets 32 is angled relative to its adjacent facet 32 at an equal angle as every other angle between facets 32. In this particular embodiment, there are six facets 32 and no more than six facets. That is, in the embodiment illustrated in FIGS. 1-5, extension member 28 consists essentially of six facets 32. The angle between adjacent facets 32 is, therefore, 60°. That is, the angle between each adjacent facet 32 is equal to 360° divided by the total number of facets in the extension member 28. Because there are a total number of six facets 32 in extension member 28, the angle between each adjacent facet 32 is 360° divided by six, which is 60°.

Preferably, each of the extension member facets 32 is configured and arranged to display clear, readable indicia. In particular, the shape of each of facets 32 is advantageous over existing die constructions in that facets 32 allow for the display of a larger, more legible number or indicia 30. While a variety of working embodiments are contemplated, in the illustrated embodiment, facets 32 have a tapered shape and configuration. That is, facets 32 are not rectangular. Preferably, facets 32 are triangular-shaped. That is, facets 32 have no more than three sides, each side being a straight edge. In other words, facets 32 are defined by, and bordered by, an outer periphery, which consists essentially of three straight sides. This provides for a triangular-shaped facet 32.

In reference now to FIG. 2, the first end cap 24 is illustrated. The first end cap 24 includes a plurality of discrete facets 36. In particular, first end cap 24 includes one-half of the number of facets of the extension member 28. In the illustrated embodiment, the extension member 28 has six facets 32. Therefore, the first end cap has three discrete facets, and no more than three facets 36. In other words, first end cap 24 consists essentially of three facets 36. Stated another way, the ratio of the number of facets of the extension member to the number of facets of the first end cap is 2:1.

Each of the first end cap facets 36 is identically shaped to every other facet 36 of the first end cap. Further, each of the first end cap facets 36 has a surface area equal to the surface area of every other facet 36 of the first end cap 24.

Each of the first end cap facets 36 is angled relative to an adjacent end cap facet 36 to define corner or edge surfaces 38 therebetween. In the particular embodiment illustrated, each of facets 36 is angled relative to its adjacent facet 36 by an angle of 120°. That is, the angle between adjacent facets 36 is equal to 360° divided by the number of facets, in this case, three. Further, the angle between adjacent facets 36 of the first end cap 24 is equal to two times or twice the angle between adjacent facets 32 of the extension member 28. Stated another way, the ratio of the angle between adjacent facets 32 in the extension member to the angle between adjacent facets 36 in the first end cap 24 is 1:2.

Each of the first end cap facets 36 is non-rectangular and non-circular. Specifically, each of the first end cap facets 36

is tapered. In the particular embodiment illustrated, each of the first end cap facets 36 is triangular-shaped. That is, each of the first end cap facets is defined by, or bordered by, a periphery of three connected straight edges. In this way, the first end cap facets 36 are defined by a triangular border, consisting essentially of three straight edges.

In reference now to FIG. 3, the second end cap 26 is illustrated. Second end cap 26 is shaped identically to the first end cap 24. That is, second end cap 26 includes three discrete facets 40, identically shaped to each other, and identically shaped as first end cap facets 36. As with the First end cap 24, the second end cap 26 has the three facets 40, and has no more than the three facets 40. Also as with the first end cap 24, the second end cap 26 includes half of the number of facets as the number of facets 32 of the extension member 28, i.e., the ratio of facets of the extension member 28 to facets of the second end cap 26 is 2:1.

Second end cap facets 40 are angled relative to adjacent facets 40 to define corners or edges 42 therebetween. As with the first end cap 24, the second end cap 26 is arranged such that the angle between adjacent facets 40 is equal to 360° divided by the number of facets (three, in the illustrated example). Therefore, second end cap facets 40 define an angle of 120° with the adjacent second end cap facet 40.

As mentioned above, second end cap facets 40 are identical in shape and appearance to first end cap facets 36, in the illustrated embodiment. As such, second end cap facets 40 are tapered. In particular, second end cap facets 40 are triangular-shaped, preferably having three non-curved, straight sides.

Referring again to FIG. 1, it can be seen that first end cap facets 36 are out of phase with second end cap facets 40. That is, the first end cap facets 36 are oriented relative to the second end cap facets 40 in an unsynchronized manner; they are not in correlation with each other. As can be seen in FIG. 1, one total facet 40 of the second end cap 26 is visible, while, in the same view, two skewed views of facets 36 of the first end cap 24 are visible.

The inventor has discovered that the configuration of the die 20 is advantageous. In particular, the shape of the end caps 24, 26 provides for more bounce when dropping die 20 onto a surface. That is, to generate a random number, the user holds die 20 above a surface at a sufficient distance, such that when die 20 is dropped onto the surface, die 20 rolls before eventually resting upon one of the facets 32 of the extension member 28. The number or indicia 30 displayed on the facet 32 which is in the uppermost position is the number which has been randomly generated. The shapes of the end caps 24, 26 provide for more bounce and randomness when die 20 is dropped onto a surface. The tapered, triangular shapes of end caps 24, 26 provide for surfaces which can abut and engage the surface on which die 20 is being dropped, to create a more interesting and amusing outcome.

Die 20 is constructed such that the center of mass of die 20 is in the precise center of symmetry of die 20. By "center of symmetry", it is meant a point that is related to a geographical figure in such a way that for any point on the figure, there is another point on the figure such that a straight line joining the two points is bisected by the original point. Each of the surface areas of discrete facets 32 of extension member 28 are equal. The combination of the center of symmetry being the center and the equal surface areas of facets 32 provides for a fair playing die. That is, no one facet 32 is more likely to be rolled than any other of the facets 32.

Preferably, each of the facets 32 has a surface area of about 0.0089 to 0.89 sq. in., typically about 0.089 sq. in.

Preferably, each of the first end cap facets **36** has a surface area of about 0.0033 to 0.33 sq. in., typically about 0.033 sq. in. As such, the ratio of the surface area of the extension member facets **32** to the surface area of each of the first end cap facets **36** is about 2.7:1. The second end cap facets **40** are identical to the first end cap facets **36**. Therefore, the second end cap facets **40** each have a surface area of about 0.0033 to 0.33 sq. in., typically about 0.033 sq. in. The ratio of the surface area of the facets **32** of the extension member **28** to the surface area of each of the second end cap facets **40** is about 2.7:1.

Die **20** is useful for generating a random number. In the illustrated embodiment, there are six discrete facets **32** on the extension member **28**. Each of the facets **32** has indicia **30** thereon, and in the illustrated embodiment, this indicia **30** is a numerical integer from one to six, inclusive. Upon shaking or rolling the die **20**, die **20** will bounce and roll around, before landing on one of its facets **32**. The facet **32** in the up position indicates the number which has been generated.

It should also be noted that the number of discrete facets **36** of the first end cap **24** is equal to one-fourth of the total number of discrete facets on the die **20**. The total number of facets on die **20** is equal to the number of facets **32** of the extension member **28**, plus the number of facets **36** of the first end cap **24**, plus the number of facets **40** of the second end cap **26**. In the embodiment of FIGS. 1-5, there are total of 12 facets (six plus three plus three=12). The number of facets on the first end cap **24** is equal to twelve divided by four, which is three. Analogously, the number of facets **40** of the second end cap **26** is equal to one-fourth of the total number of facets of the die **20**. The total number of facets of the first embodiment of FIGS. 1-5 is 12. Therefore, the number of facets of the second end cap **40** is three (12/4=3).

Preferably, the die **20** is constructed from any rigid material which holds its shape. Examples of suitable materials include glass, crystalline structure, and plastic.

Attention is now directed to FIGS. 6-9. In FIGS. 6-9, a second embodiment of a die is shown generally at **50**. Die **50** is constructed analogously to die **20**. That is, die **50** includes a first end cap **52**, a second end cap **54**, and an extension member **56** in extension therebetween. In this embodiment, however, extension member **56** defines **10**, and no more than **10**, discrete facets **58**.

Each of facets **58** includes indicia **60** thereon, indicating a number. As with the first embodiment, facets **58** of die **50** are tapered in order to more clearly display indicia **60**. In particular, facets **58** are triangular-shaped.

First end cap **52** is constructed analogously to first end cap **24**. First end cap **52** includes a number of facets **62**, which is equal to one-half of the number of facets **58** of the extension member **56**. Specifically, first end cap **52** has five discrete facets **62**, and no more than five facets **62**. First end cap facets **62** are triangular-shaped. Each of first end cap facets **62** is angled relative to an adjacent end cap facet **62** to define an angle of 72° between each.

Second end cap **54** is identical to first end cap **52**. Second end cap **54** has five discrete facets **64**. Each of facets **64** is triangular in shape, and is angled 72° with respect to an adjacent facet **64**.

As similarly described with respect to the first embodiment, in this embodiment the facets **62** on the first end cap **52** are out of phase with the facets **64** on the second end cap **54**.

Preferably, the surface area of each of facets **58** of extension member **56** is about 0.0106 to 1.06 sq. in.,

typically about 0.106 sq. in. The surface area of each of first end cap facets **62** is about 0.0046 to 0.46 sq. in., typically about 0.046 sq. in. Second end cap facets **64** are identical to first end cap facets **62**. As such, each of second end cap facets **64** has a surface area of about 0.0046 to 0.46 sq. in., typically about 0.046 sq. in. The ratio of the surface area of one facet **58** to one facet **62** is about 2.3:1. This is the same ratio as the ratio of facet **58** to facet **64**.

As with the first embodiment of the die, die **50** is constructed so that the center of mass is in the precise geometric center of die **50**. Further, each of facets **58** has an identical and equal surface area. This provides for a fair playing die.

Die **50** has a total of **20** facets. That is, extension member **56** has ten facets, first end cap has five facets, and second end cap has five facets. Therefore, the total number of facets is: 10+5+5=20. The number of facets of each of the first and second end caps **52**, **54** is equal to one-fourth of the total number of facets of die **50**. Thus, since there are a total of **20** facets, the number of facets of first end cap **52** can be derived by dividing by four, which is five. Analogously, the number of facets of the second end cap **54** may be derived by dividing the total number of facets (**20**) by four, which is five.

Die **50** is used analogously as die **20**. That is, die **50** is dropped at a height above a surface sufficient to cause die **50** to roll around. Ultimately, die **50** will rest upon one of its extension member facets **58**. This will leave one of its extension member facets **58** in the uppermost position. The number displayed on the facet in the uppermost position is the number generated. In the example illustrated, this would be an integer from 1 through 10, inclusive.

Attention is now directed to FIGS. 10-13. In FIGS. 10-13, a third embodiment of a die is shown generally at **70**. Die **70** is constructed analogously to die **20** and die **50**.

That is, die **70** includes a first end cap **72**, a second end cap **74**, and an extension member **76** in extension therebetween. In this embodiment, however, extension member **76** defines **20**, and no more than **20**, discrete facets **78**.

Each of facets **78** includes indicia **80** thereon, indicating a number. As with the first and second embodiments, facets **78** of die **70** are tapered in order to more clearly display indicia **80**. In particular, facets **78** are triangular-shaped.

First end cap **72** is constructed analogously to first end cap **24** (FIG. 1) and first end cap **52** (FIG. 6). First end cap **72** includes a number of facets **82**, which is equal to one-half of the number of facets **78** of the extension member **76**. Specifically, first end cap **72** has ten discrete facets **82**, and no more than ten facets **82**. First end cap facets **82** are triangular-shaped. Each of first end cap facets **82** is angled relative to an adjacent end cap facet **82** to define an angle of 36° between each.

Second end cap **74** is identical to first end cap **72**. Second end cap **74** has ten discrete facets **84**. Each of facets **84** is triangular in shape, and is angled 36° with respect to an adjacent facet **84**.

As described with respect to the first and second embodiments, in this embodiment, the facets **82** on the first end cap **72** are out of phase with the facets **84** on the second end cap **74**.

Preferably, the surface area of each of facets **78** of extension member **76** is about 0.0116 to 1.16 sq. in., typically about 0.116 sq. in. The surface area of each of first end cap facets **82** is about 0.0056 to 0.56 sq. in. typically about 0.056 sq. in. Second end cap facets **84** are identical to

first end cap facets **82**. As such, each of second end cap facets **84** has a surface area of about 0.0056 to 0.56 sq. in., typically about 0.056 sq. in. The ratio of the surface area of one facet **78** to one facet **82** is about 2.06:1. This is the same ratio as the ratio of facet **78** to facet **84**.
5

As with the first and second embodiments of the die, die **70** is constructed so that the center of mass is in the precise geometric center of die **70**. Further, each of facets **78** has an identical and equal surface area. This provides for a fair playing die.
10

Die **70** has a total of **40** facets. That is, extension member **76** has twenty facets, first end cap has ten facets, and second end cap has ten facets. Therefore, the total number of facets is: $20+10+10=40$. The number of facets of each of the first and second end caps **72**, **74** is equal to one-fourth of the total number of facets of die **70**. Thus, since there are a total of **40** facets, the number of facets of first end cap **72** can be derived by dividing by four, which is ten. Analogously, the number of facets of the second end cap **74** may be derived by dividing the total number of facets (**20**) by four, which is ten.
15

Die **70** is used analogously as die **20** and die **50**. That is, die **70** is dropped at a height above a surface sufficient to cause die **70** to roll around. Ultimately, die **70** will rest upon one of its extension member facets **78**. This will leave one of its extension member facets **78** in the uppermost position. The number displayed on the facet in the uppermost position is the number generated. In the example illustrated, this would be an integer from 1 through 20, inclusive.
20

Other embodiments of the invention will be apparent to those skilled in the art from consideration of the specification and practice of the invention disclosed herein. In particular, one skilled in the art will understand that die constructions having extension member facets totaling **8**, **12**, **30** and other even multiples can be constructed according to the principles taught herein.
25

It is intended that the specification and examples be considered as exemplary only, with a true scope and spirit of the invention being indicated by the following claims.
30

I claim:

1. A die construction comprising:

- (a) a body having first and second, opposite end caps and an extension member therebetween;
45
- (b) said extension member having a first number of discrete facets and no more than said first number;
  - (i) each of said discrete facets being identically shaped and having equal surface areas;
- (c) said first end cap having a second number of discrete facets and no more than said second number; said second number being one-half of said first number;
  - (i) each of said first end cap discrete facets being identically shaped and having equal surface areas;
50
- (d) said second end cap having said second number of discrete facets and no more than said second number;
  - (i) each of said second end cap discrete facets being shaped identically as said first end cap discrete facets; and each of said second end cap discrete facets having a surface area equal a surface area of each of said first end cap discrete facets; and
55
- (e) each of said discrete facets of said extension member having a surface area that is different from a surface area of each of said discrete facets of said first and second end caps.
60

2. A die construction according to claim 1, wherein:
  - (a) each of said extension member discrete facets include printed indicia thereon.
3. A die construction according to claim 2, wherein:
  - (a) each of said extension member discrete facets is tapered.
4. A die construction according to claim 3, wherein:
  - (a) each of said extension member discrete facets is triangular-shaped.
5. A die construction according to claim 4, wherein:
  - (a) each of said first end cap discrete facets and said second end cap discrete facets is tapered.
6. A die construction according to claim 5, wherein:
  - (a) each of said first end cap discrete facets and said second end cap discrete facets is triangular-shaped.
7. A die construction according to claim 6, wherein:
  - (a) said first number is six; and said second number is three.
8. A die construction according to claim 7, wherein:
  - (a) each of said extension member discrete facets has a surface area of about 0.0089–0.89 sq. in.
9. A die construction according to claim 8, wherein:
  - (a) each of said first end cap discrete facets has a surface area of about 0.0033–0.33 sq. in.; and
  - (b) each of said second end cap discrete facets has a surface area of about 0.0033–0.33 sq. in.
10. A die construction according to claim 6, wherein:
  - (a) said first number is ten; and said second number is five.
11. A die construction according to claim 10, wherein:
  - (a) each of said extension member discrete facets has a surface area of about 0.0106–1.06 sq. in.
12. A die construction according to claim 11, wherein:
  - (a) each of said first end cap discrete facets has a surface area of about 0.0046–0.46 sq. in.; and
  - (b) each of said second end cap discrete facets has a surface area of about 0.0046–0.46 sq. in.
13. A die construction according to claim 6, wherein:
  - (a) said first number is twenty; and said second number is ten.
14. A die construction according to claim 13, wherein:
  - (a) each of said extension member discrete facets has a surface area of about 0.0116–1.16 sq. in.
15. A die construction according to claim 14, wherein:
  - (a) each of said first end cap discrete facets has a surface area of about 0.0056–0.56 sq. in.; and
  - (b) each of said second end cap discrete facets has a surface area of about 0.0056–0.56 sq. in.
16. A die construction according to claim 1, wherein:
  - (a) a ratio of a surface area of each of said extension member facets to a surface area of each of said first end cap discrete facets is about 2–3:1.
17. A die comprising:
  - (a) a body including a first end cap, a second end cap, and an extension member in extension therebetween;
  - (b) said first end cap including a first number of facets and no more than said first number; said second end cap including a second number of facets and no more than said second number; and said extension member defining a third number of facets and no more than said third number;
    - (i) said first number being equal to one-fourth of a total of said first number and said second number and said third number;

9

- (ii) said second number being equal to one-fourth of the total of said first number and said second number and said third number;
- (iii) each of said extension member facets being equal in surface area; 5
- (iv) each of said extension member facets being triangular-shaped;
- (v) each of said extension member facets having indicia thereon indicating a number; and
- (vi) each of said extension member facets having a surface area that is different from a surface area of each of said first and second end cap facets. 10

10

- 18.** A die according to claim 17, wherein:
  - (a) each of said first end cap facets is triangular-shaped; and
  - (b) each of said second end cap facets is triangular-shaped.
- 19.** A die according to claim 17, wherein:
  - (a) said third number is six.
- 20.** A die according to claim 17, wherein:
  - (a) said first number, said second number, and said third number total 40.

UNITED STATES PATENT AND TRADEMARK OFFICE
CERTIFICATE OF CORRECTION

PATENT NO. : 5,938,197
DATED : August 17, 1999
INVENTOR(S) : Bowling

Page 1 of 1

It is certified that error appears in the above-identified patent and that said Letters Patent is hereby corrected as shown below:

Column 4,

Line 11: "First" should read -- first --.

Column 7, claim 1:

Line 55: delete "and" after word "areas;".

Line 62: insert -- to -- after the word "equal".

Signed and Sealed this

Twenty-first Day of August, 2001

(57) ABSTRACT

A die construction includes a body having first and second, opposite end caps and an extension member therebetween. The extension member has a first number of discrete facets and no more than the first number. Each of the discrete facets is identically shaped and have equal surface areas. The first end cap has a second number of discrete facets and no more than the second number. The second number is one-half of the first number. Each of the first end cap discrete facets is identically shaped and has an equal surface area to one another. The second end cap has the second number of discrete facets, that is, the same number as the first end cap, and has no more than the second number. Each of the second end cap discrete facets is identically shaped as the first end cap discrete facets. Each of the second end cap discrete facets has a surface area equal to a surface area of each of the first end cap discrete facets.

EX PARTE
REEXAMINATION CERTIFICATE
ISSUED UNDER 35 U.S.C. 307

THE PATENT IS HEREBY AMENDED AS
 INDICATED BELOW.

Matter enclosed in heavy brackets [ ] appeared in the patent, but has been deleted and is no longer a part of the patent; matter printed in italics indicates additions made to the patent.

AS A RESULT OF REEXAMINATION, IT HAS BEEN DETERMINED THAT:

The patentability of claims **17–20** is confirmed.

Claim **2** is cancelled.

Claim **1** and **3** are determined to be patentable as amended.

Claims **4–16**, dependent on an amended claim, are determined to be patentable.

1. A die construction comprising:

(a) a body having first and second, opposite end caps and an extension member therebetween;

5

(b) said extension member having a first number of discrete facets and no more than said first number;

(i) each of said discrete facets being identically shaped and having equal surface areas;

(c) said first end cap having a second number of discrete facets and no more than said second number; said second number being one-half of said first number;

(i) each of said first end cap discrete facets being identically shaped and having equal surface areas;

(d) said second end cap having said second number of discrete facets and no more than said second number;

(i) each of said second end cap discrete facets being shaped identically as said first end cap discrete facets; and each of said second end cap discrete facets having a surface area equal to a surface area of each of said first end cap discrete facets; and

(e) each of said discrete facets of said extension member having a surface area that is different from a surface area of each of said discrete facets of said first and second end caps;

(f) *wherein each of said extension member discrete facets includes printed indicia thereon.*

3. A die construction according to claim **[2] 1**, wherein:

(a) each of said extension member discrete facets is tapered.
